EYEGLASS FRAME FRONT

John D. Baer, Attleboro, Mass., assignor, by mesne assignments, to The Univis Bishop Company, North Attleboro, Mass., a corporation of Massachusetts

Filed Nov. 13, 1961, Ser. No. 67,483

Term of patent 14 years

(Cl. D57—1)

FIG. 1.

FIG. 2.

FIG. 3.

FIG. 1 is a top plan view of an eyeglass frame front showing my new design;

FIG. 2 is a front elevational view thereof; and

FIG. 3 is a cross-sectional view taken along line 3—3 of FIG. 2 on an enlarged scale.

The dominant features of my design reside in the portions shown in full lines, consisting of ornamentation which is embedded within the top of the lens-holding portions of the frame front as shown.

I claim:

The ornamental design for an eyeglass frame front, as shown and described.
